UNITED STATES PATENT OFFICE.

CHRISTIAN CELSUS FOSS, OF PULASKI, AND DOUGLAS DEWEY DE LOACH, OF SAVANNAH, GEORGIA.

ROTARY VALVE.

Application filed September 7, 1923. Serial No. 661,411.

To all whom it may concern:

Be it known that we, CHRISTIAN C. Foss and DOUGLAS D. DE LOACH, citizens of the United States, and residents, respectively, of Pulaski, in the county of Candler and State of Georgia, and Savannah, in the county of Chatham and State of Georgia, have invented certain new and useful Improvements in Rotary Valves, of which the following is a specification.

Our invention relates to improvements in rotary valves and more particularly to improvements in rotary valves for internal combustion engines, and it consists in the combinations, constructions and arrangements herein described and claimed.

An object of our invention is to provide an improved rotary valve construction for internal combustion engines which will afford facilities for controlling the delivery of a combustible fluid charge to one or more cylinders of an engine and the discharge of exhaust gases from the cylinder or cylinders of the engine without possibility of sticking or undue friction between the relatively moving parts of the valve mechanism, irrespective of the number of cylinders which are comprised in the engine with which the valve mechanism may be associated.

A further object of the invention is to provide a rotary valve mechanism of the character described which includes means automatically adjustable to compensate for wear on the relatively moving parts of the valve mechanism as well as for unequal expansion or contraction of the relatively moving parts, whereby leakage of the intake or exhaust gases from the valve mechanism is prevented.

A further object of the invention is to provide a rotary valve mechanism of the character described in which the rotating valves will be supported anti-frictionally in its casing and will turn smoothly and quietly therein.

A further object of the invention is to provide in a rotary valve mechanism of the character described a novel packing ring which is self-adjusting to compensate for wear on or unequal expansion or contraction of the rotating valve and the valve casing and which effectively prevents leakage of gases between the valve and the valve

casing at a desirable place along the length of the latter.

A further object of the invention is to provide a mechanism of the character described which is constructed in such manner that a suitable lubricant may be conveniently supplied to the relatively moving surfaces of the valve mechanism without permitting leakage of gases between such surfaces.

A still further object of the invention is to provide in a rotary valve mechanism of the character described, a novel drive arrangement for transmitting power from a moving part of the engine to the rotatable valve, the drive mechanism also including means for supporting a distributor for intermittently connecting the spark plugs of the respective cylinders of the engine with an ignition circuit.

Other objects and advantages of the invention will be apparent from the following description, considered in conjunction with the accompanying drawings, in which—

Figure 1 is a view, mainly in vertical section and partly in side elevation, showing a practical embodiment of the invention operatively applied to an internal combustion engine, only portions of the latter being exhibited.

Figure 2 is a section along the line 2—2 of Figure 1.

one of two complementary sections of a liner which is comprised in the valve casing of the second form of the device,

Figure 11 is a face view of an expandible packing member and

Figure 12 is a fragmentary perspective group view showing in separated position the elements of the expandible packing member which is exhibited in Figure 11.

10 Referring now to the drawings, we show in Fig. 1 a portion of an engine block 1 which is formed to provide a plurality of cylinders which are indicated at 2, 3, 4 and 5 respectively. Each of the cylinders is 15 provided with an intake port and an exhaust port which extend through the head of the cylinder and establish communication between the interior of the latter and the interior of the valve casing 6 which extends 20 across the head of the respective cylinders, the intake and exhaust ports for the cylinder 4 being shown in Figure 2 and being indicated at 7 and 8 respectively. The valve casing 6 preferably comprises an outer tubular member consisting of a base portion 9 which may be formed integrally with the engine block and a cap portion 10 which is 25 complementary to the base portion 9, the base portion and the cap portion being provided 30 at their meeting edges with radially extending portions which may be secured together by bolts 11 as best seen in Figures 2 and 3.

The valve casing 6 also is provided with a water jacket 12 which may have communication at any suitable number of points with a water manifold or supply conduit 13 and which also may be in open communication and continuous with the water jacket 14 of the cylinders, as clearly shown in Figures 2 and 3.

The valve casing also comprises an inner tubular member or liner which consists of two complementary segmental sections 15 and 16 respectively, the former of 45 which has the outer wall thereof coextensive in area with the inner wall of the base portion 9 of the outer casing member while the outer wall of the section 16 is coextensive in area with the inner wall of the cap portion 10 of the outer casing member and the sections 15 and 16 respectively are secured in close interfitting relation to the base portion 9 and the cap portion 10 of the outer casing member so that the meeting edges of the sections 15 and 16 are in contact with each other in the plane of the meeting edges of the base portion 9 and the cap portion 10.

The valve casing 6 is provided at suitable 50 places along its length with sets of ports opening through the upper side thereof, each of the sets of ports consisting of an intake port located diametrically opposite the intake port 7 for one of the cylinders 55 and an exhaust port located diametrically

opposite the exhaust port 8 of the same cylinder. It is to be understood that there is a set of the ports through the upper part of the valve casing for each of the cylinders across which the valve casing extends. 70 In Figure 2, we show the set of ports in the upper part of the valve casing for the cylinder 4, the intake port of said set being designated 17 and the exhaust port indicated at 18. The intake port 17 is shown as being 75 in open communication with a conduit 19 which in actual practice is a branch of the intake manifold of the engine. The exhaust conduit 18 also is shown in open communication with a conduit 20 which in practice is a branch of the exhaust manifold of the engine.

It is desirable that the intake gases should pass direct from the conduit 19 through the intake ports 17 direct to the intake port 80 7 and thence into the explosion chamber of the cylinder at the proper time without any appreciable quantity of the gas being permitted to move longitudinally of the valve casing as otherwise loss of compression may 85 ensue and the operation of the engine thus be detrimentally affected. To this end, our invention provides novel valve and packing means rotatably supported within the valve casing and cooperating with the latter to 90 insure the delivery of the combustible intake gases to each cylinder at the proper time without there being any leakage of the gases during the passage thereof from the intake port 17 for each cylinder to the 95 opposite intake port 7 of the cylinder, the valve and packing means also insuring the complete charge of the exhaust gases from each cylinder at a proper time. The valve means embodied in the form of the device 100 which is exhibited in Figures 1, 2, 3 and 5 comprises a carrying member which is designated generally 21 (see Figure 4). The carrying member 21 may comprise two 105 axially aligned interengaged sections 22 and 23 respectively for convenience in removing the carrying member from the valve casing and replacing it in the latter when desired. The section 22 has the form of a hollow tube or cylinder reduced diametrically at 110 its ends and merged into axially aligned solid or shaft portions 22^a and 22^b respectively. The section 23 also has the form of a hollow tube or cylinder reduced diametrically at its ends and merged into axially aligned oppositely extending solid or shaft portions 23^a and 23^b respectively. The solid or shaft portions of the sections 22^a or 22^b are also in axial alignment with the hollow tubular section. The solid or shaft portions 115 23^a and 23^b respectively of the section 23 also are in axial alignment with the section 23. The sections 22 and 23 are equal in diameter. The shaft portion 23^b is enlarged at its extremity as indicated at 120 24,

the enlargement being provided with a tongue extension 25 which is adapted to enter a socket 26 in the end of an enlargement 27 of the shaft portion 22^a at the outer end of the latter. The sections 22 and 23 may thus be coupled together to rotate as a unit. The shaft portion 22^a is enlarged adjacent to its end as indicated at 28. The shaft portion 23^a is enlarged adjacent to its end as indicated at 29. The enlargements 28, 29 and 27-24 are circular in cross sectional contour and equal in diameter so that the carrying member 21 will be supported to rotate about its longitudinal axis when the respective enlargements just enumerated are supported anti-frictionally as at 30 in bearings or journal boxes 31, 32 and 33 respectively which are carried by the engine block 1 and are disposed in axial alignment with one another and with the bore of the valve casing 6. With this arrangement, the carrying member 21 will be disposed in concentric relation to the bore of the valve casing 6 and the diameter 25 of the tubular sections 22 and 23 of the carrying member is such that the outer faces of these sections will have a close sliding fit within the inner tubular member of the valve casing.

30 The carrying member 21 may be driven at a speed which will vary with the speed of the engine by power derived from a moving part of the engine and transmitted to the carrying member by means of a vertical shaft 34 which carries a worm 35 in mesh with a worm wheel 36 on a shaft portion of the carrying member. In the embodiment of the invention shown in Figure 1, the shaft 34 extends above the level of the carrying member 21 and the upper end portion of the shaft 34 is fashioned, as at 37 to support the usual distributor not shown for connecting the spark plugs of the respective cylinders intermittently with an ignition circuit.

45 The section 22 of the carrying member 21 is adapted to overlie the cylinders 2 and 3 while the section 23 is adapted to overlie the cylinders 4 and 5. However, it will be understood that the hollow tubular portions or the section of the carrying member which our invention provides may be of any length required to adapt the carrying member for cooperation with a valve casing which extends across one or more cylinders. The hollow tubular portion of the carrying member which extends within the valve casing 6 above the cylinder 4 is illustrated in Figure 2 and will be described in detail, it being understood that the hollow tubular portions of the carrying member which respectively extend within the valve casing 6 above the remaining cylinders are identical in construction and operation in essential respects with the portion of the tubular

carrying member which is shown in Figure 2. The same reference numerals therefore have been used to designate like parts of the portions of the carrying member which extend within the valve casing 6 above the respective cylinders. Each of these portions of the carrying member is provided with spaced apart peripheral grooves 38 in its outer face, the distance between each two adjacent grooves being greater than the diameter of the underlying cylinder. Diametrically opposite recesses 39 and 40 respectively extend longitudinally of the carrying member in the outer face of the latter between each two adjacent grooves 38. A port 41 extends radially from the bottom wall of each recess 39 to the inner wall of the carrying member. A port 42 of equal area extends from the bottom of the recess 40 through the walls of the carrying member and opens into the interior of the latter. An expandible valve head designated generally 43 is provided for each of the cylinders and comprises two cooperative hollow sections 44 and 45 respectively. The hollow section 44 is adapted adjacent to one end thereof to slidably interfit the section 45. The section 44 is enlarged adjacent to its other end as indicated at 46 to closely interfit the port 39 and is further enlarged at its outer end as indicated at 47 to interfit the recess 39, the enlargement 47 being in the nature of a continuous flange which is curved arcuately in cross sectional contour so that the outer face thereof will closely contact at all points with the inner wall of the inner member of the valve casing. The section 45 is enlarged adjacent to its outer end as indicated at 48 to closely interfit the opening or port 42 and is further enlarged at its outer end to provide a flange 49, the enlargement 49 being adapted to interfit the recess 40 and being arcuately curved in cross sectional contour so that the outer face thereof will conform in curvature to the inner wall of the valve casing 6. Expansion springs 50 are disposed between the enlargements 46 and 48 of each expandible valve head, being retained in position by inwardly extending lugs 51 carried by the enlargements 46 and 48 and engaging with the end portions of the expansion springs. The expansion springs of each expandible valve head urge the sections of the latter apart continuously and thus tend to hold the outer faces of the sections of each valve head in close contact with the inner wall of the valve casing. A pair of expandible packing rings 52 are provided for cooperation with each of the expandible valve heads. Each expandible ring 52 is of the split ring type of construction and comprises two complementary segmental sections 53 and 54 re-

spectively, these sections having overlapping slidably engaging reduced portions at the meeting ends as best seen in Figure 7. The outer diameter of each of the expandable rings 52 is such that the ring will be partially received in a groove 55 in the inner wall of the inner tubular member 15-16 of the valve casing when the expandable ring is also partially received in the groove 38 which is in concentric relation to the groove 55. It of course is to be understood that there is a groove 55 in the inner face of the inner tubular member of the valve casing in concentric relation with each of the grooves 38 in the outer peripheral wall of the carrying member. Rods 56 extend in chord-like relation to each of the rings 52 and each rod has the end portions thereof received in sockets in the inner walls of the rings. Each rod 56 is enlarged intermediate its length as indicated at 57 to provide a stop. Expansion springs 58 are disposed on each rod 56 between opposite ends of the stop 57 and slideable collars 59 which work through openings 60 in the wall of the carrying members 21 and urge the slideable collars 59 outwardly against the sections of the expandable ring, thereby tending to expand the latter.

As illustrated to advantage in Figure 5, the pair of expandable rings with which each of the expandable valve heads 43 is associated are in close sliding contact with the enlarged end portions 47 and 49 of the sections of the expandable valve head at opposite ends of the latter.

From the foregoing description of the various parts the operation thereof may be readily understood. The carrying member 21 will be rotated so that the expandable valve head for each cylinder will be disposed at the proper time in position to permit passage of combustible gases from the intake port 17 through the expandable valve head to the intake port 7, thence into the cylinder. As the rotational movement of the carrying member continues, compression will take place within the cylinder and any of the compressed charge which may pass between the wall of the carrying member and the inner wall of the valve casing between each pair of packing rings 52 will be confined by the latter within the space between such adjacent packing rings, whereby there will be no appreciable lessening of compression within the cylinder. As the rotation of the carrying member 21 is continued, the expandable valve head will be disposed in position to connect the exhaust port 8 of the cylinder with the exhaust port 18 of the valve casing. The expandable valve head will be adjusted automatically because of the action of the expansion springs 50 to compensate for wear on the

outer faces thereof or on the inner wall of the valve casing and to also compensate for unequal expansion of the carrying member 21 or the expandable valve head and the valve casing. Likewise each packing ring 52 will be adjusted automatically to compensate for wear thereon or on the portion of the valve casing which is in contact therewith or to compensate for unequal expansion or contraction of these relatively moving parts. Smooth and efficient operation of a valve mechanism embodying the invention at all times thus are assured.

It is desirable that the relatively moving parts of the valve mechanism shall be kept in a lubricated condition without permitting the escape of gases between these parts and to this end each of the expandable rings 52 is provided with a groove 61 in the outer peripheral wall thereof, which groove is in communication with a supply duct 62 leading thereto through the upper part of the valve casing and with a discharge duct 63 which may lead therefrom to the lower part of the valve casing, as best seen in Figure 5. The groove 61 is in communication with passages 64 which extend radially in each ring part of the way through the latter and then laterally toward the adjacent expandable valve head. The latter is provided with transverse passages in the enlarged end portions 47 and 49 of the sections thereof as indicated at 65 and 66 in Figure 5, the last named passages opening through the outer faces of the expandable valve head, whereby the lubricant will be fed between the relatively moving parts of the device.

In the form of the device which is illustrated in Figure 8, the valve casing is designated generally at 60 and comprises an outer shell member 61 and an inner tubular member or liner 62 which respectively are identical in essential respects with the corresponding members of the valve casing 6, the outer tubular members 61 being provided with a water jacket 63 which is in communication with the water jacket 14 of the engine block, as best seen in Figure 9. The outer tubular valve casing member 61 and the inner tubular valve casing member 62 are made up of complementary sections as in the case of the inner and outer tubular members of the valve casing 6. In Figure 10, we show one of the two similar sections of the inner tubular valve casing member or liner 62 and in the drawing we have designated the sections of the latter 62a. It will be observed by referring to Figure 8 that the valve casing 60 differs from the valve casing 6 in that the set of intake ports for each cylinder is in alignment longitudinally of the valve casing with the set of exhaust ports for the cylinder instead of being in staggered relation in respect thereto, as in the case of the valve casing 6. The intake ports which

open through the upper part of the valve casing 60 for each cylinder is designated 65, the exhaust port which opens through the upper part of the valve casing 60 for each cylinder is indicated at 66, and 67 and 68 respectively designate the intake port and the exhaust port through the lower part of the valve casing 60 into each cylinder. It will be observed that the intake ports 65 and 67 for each cylinder are diametrically opposite each other and that the exhaust ports 66 and 68 for each cylinder also are diametrically opposite each other and in the same plane as the intake ports for that particular cylinder. The valve of the form of the device illustrated in Figures 8 and 9 comprises a carrying member 69 which in essential respects differs from the carrying member 21 only in that it is provided with two openings indicated in Figure 9 at 70 and 71 respectively through the upper part of the portion thereof overlying each cylinder, the openings 70 and 71 being respectively diametrically opposite openings 72 and 73 in the lower part of the portion of the carrying member which overlies the cylinder, instead of having only one opening through the upper part of the portion of the carrying member which overlies each cylinder in alignment with a diametrically opposite opening through the lower part of that portion, as in the case of the carrying member 21. The openings 70 and 71 for each cylinder are spaced apart slightly longitudinally of the carrying member and also circumferentially of the carrying member, the openings 72 and 73 for each cylinder of course being similarly spaced, and the openings 70 and 71 for each cylinder respectively open at their outer ends through recesses 74 and 75 in the outer face of the carrying member, the recesses 74 and 75 being merged into each other at their adjacent ends as best seen in Figure 8.

The openings 72 and 73 likewise open through the bottoms of recesses 76 and 77 respectively which also are merged into each other at their adjacent ends. An expandible valve head 78 extends diametrically of the carrying member 69 for each cylinder and has enlarged portions received in the openings 70 and 72 and further enlarged end portions 79 respectively interfitting the recesses 75 and 77. A similar expandible valve head 80 also is provided for each cylinder and extends diametrically of the carrying member 69, having enlarged portions received in the openings 71 and 73 and further enlarged end portions 81 respectively interfitting the recesses 74 and 76. Corresponding end portions 79 and 81 of the valve heads 78 and 80 for each cylinder interlap slightly at their adjacent ends and have cut out portions interengaging as indicated at 82 in Figure 8.

The outer peripheral face of each of the end

portions 79 and 81 is curved to conform to the curvature of the inner wall of the contiguous valve casing 60 and each of the expandible valve heads 78 and 80 is identical in construction in essential respects with the expandible valve head 43 of the preferred form of the device, each comprising two cooperative sections spring pressed apart.

Disposed within the valve casing at opposite ends of each set of expandible valve heads 78 and 80 are expandible packing rings such as that indicated at 83 in Figure 11. Each packing ring 83 is made up of two separable overlapping half portions, each of which comprises three segmental sections indicated at 84, 85 and 86 respectively. The sections 84 and 86 are hingedly attached to the ends of the section 85, as indicated at 87 and the meeting ends of the sections 84 and 86 of each of the separable half portions of the ring are reduced and overlapped as indicated at 88. The sections 85 have transverse openings therethrough engaged by tongues 90 on the adjacent ends of one of the expandible valve heads 78 or 80 when a pair of the rings 83 are disposed in abutting relation to opposite ends of the expandible valve heads 78 and 80 of each set. Each of the rings 83 is partially received in a groove 91 in the inner wall of the valve casing 60 and also is partially received in a cooperating groove in the outer wall of the carrying member 69, as in the case of the ring 62 in the preferred form of the device. A disk 91 is provided for each of the rings 83 and is disposed within the carrying member, being provided with diametrically opposite sockets 92 in which are secured expansion springs 93 which protrude through openings in the walls of the carrying member and engage at their outer ends with the lapped end portions of sections 84, 86 of the rings. Each expandible ring 83 thus will be expanded both because of the action of the springs 93 and the action of the expandible valve head 78 or 80 with which it is associated since the lapped sections 84, 86 will be urged outwardly by the springs 93 and the sections 85 will be urged apart as the particular valve head with which the ring is associated is expanded and pulled together or toward each other as the expandible valve head is contracted in length for any reason.

Obviously, our invention is susceptible of embodiment in forms other than those illustrated in the accompanying drawing and we therefore consider as our own all modifications and adaptations of the forms of the device herein disclosed which fairly fall within the scope of the appended claims.

We claim:

1. A rotary valve comprising a tubular valve casing having diametrically opposite

ports formed through the walls thereof, and a valve comprising a carrying member mounted to rotate in the casing and having diametrically opposite openings respectively adapted to register at times with the corresponding openings of the valve casing and radially expansible means extending through diametrically opposite openings in the carrying member in engagement with the inner wall of the valve casing, said radially expansible means being provided with an opening extending therethrough for establishing communication between the diametrically opposite ports of the valve casing at a certain time during rotation of the carrying member.

2. A rotary valve comprising a tubular valve casing having diametrically opposite ports formed through the walls thereof, and a valve comprising a carrying member mounted to rotate in the casing and having diametrically opposite openings respectively adapted to register at times with the corresponding openings of the valve casing and radially expansible means extending through diametrically opposite openings in the carrying member in engagement with the inner wall of the valve casing, said radially expansible means having an opening therethrough for establishing communication between diametrically opposite ports of the valve casing at a certain time during rotation of the carrying member, said expansible means comprising two partially overlapping slidably engaging sections spring pressed apart continuously.

3. A rotary valve for multi-cylinder internal combustion engines comprising a hollow valve casing extending across the upper ends of the respective cylinders and being provided with an exhaust port and an intake port opening through the lower part thereof into each cylinder, said valve casing also being provided with an intake port and an exhaust port opening through the upper part thereof for each cylinder, the second named intake port being diametrically opposite the first named intake port for the same cylinder and the second named exhaust port for each cylinder being diametrically opposite the first named exhaust port for the same cylinder, and valve means for controlling communication between the respective intake ports and between the respective exhaust ports for each cylinder, said valve means comprising a carrying member rotatably supported in position to extend within the valve casing, and a radially expansible hollow valve head carried by the carrying member in position to engage with the inner wall of the valve casing and to establish communication between the intake ports of each set at a certain period during each revolution of the carrying member to establish com-

munication between the respective exhaust ports of each set during another period in each revolution of the carrying member.

4. A rotary valve for multi-cylinder engines comprising a valve casing having a bore extending across the upper ends of the cylinders, said bore being circular in cross sectional contour and having spaced apart annular grooves therein, the portion of the bore extending between two adjacent annular grooves overlying the upper end of one of the cylinders, an elongated carrying member adapted to extend through said bore and to protrude from the opposite end of the latter, means for supporting said carrying member anti-frictionally to rotate in concentric relation to the bore, said carrying member including tubular portions having spaced apart peripheral grooves corresponding in number and arrangement to the grooves in the bore of the casing, each groove in the peripheral wall of the carrying member being in concentric confronting relation to one of the grooves in the bore of the valve casing, said valve casing having an intake port and an exhaust port opening through the lower part thereof for each cylinder to establish communication between the interior of the cylinder and the interior of the valve casing and said valve casing also having a second intake port and a second exhaust port for each cylinder, the second exhaust port opening through the upper part of the valve casing in diametrically opposite relation to the intake port through the lower part of the valve casing and the exhaust port through the upper part of the valve casing being diametrically opposite to the exhaust port in the lower part of the valve casing for each cylinder, each portion of the carrying member extending between adjacent grooves having diametrically extending openings respectively adapted to register with the intake ports for one cylinder when the carrying member has been rotated to one position in the valve casing and to register with the exhaust port in the valve casing for that cylinder when the carrying member has been rotated to another position, and a hollow radially expansible valve head working through the opening of the carrying member for conducting gases between said intake ports of each cylinder when the carrying member is in the first named position and for conducting gases between the exhaust ports of the cylinder when the carrying member is in the second named position.

5. A rotary valve for multi-cylinder engines comprising a valve casing having a bore extending across the upper ends of the cylinders, said bore being circular in cross sectional contour and having spaced apart sets of diametrically opposite ports through

the portion thereof overlying each cylinder there being a set of intake ports and a set of exhaust ports for each cylinder, an elongated carrying member supported to rotate in the valve casing in concentric relation to the latter, and a hollow radially expandible valve head supported by the carrying member for conducting gases between said intake ports of each cylinder when the carrying member has been rotated to one position and for conducting gases between the exhaust ports of the cylinder when the carrying member is in another named position, and means whereby the carrying member may be rotated at a speed proportionate to the speed of the engine.

6. A rotary valve for multi-cylinder engines comprising a valve casing having a bore extending across the upper ends of the cylinders, said bore being circular in cross sectional contour and having spaced apart annular grooves therein, the portion of the bore extending between two adjacent annular grooves overlying the upper end of one of the cylinders, an elongated carrying member adapted to extend through said bore and to protrude from the opposite end of the latter, means for supporting said carrying member anti-frictionally to rotate in concentric relation to the bore, said carrying member including tubular portions having spaced apart peripheral grooves corresponding in number and arrangement to the grooves in the bore of the casing, each groove in the peripheral wall of the carrying member being in concentric confronting relation to one of the grooves in the bore of the valve casing, said valve casing having an intake port and an exhaust port opening through the lower part thereof for each cylinder to establish communication between the interior of the cylinder and the interior of the valve casing and said valve casing also having a second intake port and a second exhaust port for each cylinder, the second exhaust port opening through the upper part of the valve casing in diametrically opposite relation to the intake port through the lower part of the valve casing and the exhaust port through the upper part of the valve casing being diametrically opposite to the exhaust port in the lower part of the valve casing for each cylinder, each portion of the carrying member extending between adjacent grooves having diametrically extending openings respectively adapted to register with the intake ports of one cylinder when the carrying member has been rotated to one position in the valve casing and to register with the exhaust port in the valve casing for that cylinder when the carrying member has been rotated to another position, and a hollow radially expandible valve head working through the opening of the carrying member for conducting gases between said intake port of each cylinder when the carrying member is in the first named position and for conducting gases between the exhaust ports of the cylinder when the carrying member is in the second named position, and means whereby the carrying member may be rotated at a speed proportionate to the speed of the engine, and packing means arranged between corresponding grooves in the carrying member and the bore of the valve casing.

7. In a rotary valve, a valve casing extending transversely across the upper end of the cylinder of a combustion engine, said valve casing having a bore circular in cross sectional contour, said valve casing having a port opening through the lower part thereof into the interior of the cylinder and having a second port opening into the upper part thereof in diametrically opposite relation to the first named port, a carrying member having a cylindrical portion extending through said valve casing and having a pair of peripheral grooves in its outer wall, said grooves being respectively located in planes extending at opposite sides of the cylinder and said carrying member having diametrically opposite recesses in its peripheral wall extending longitudinally thereof between said grooves and also having a pair of openings extending respectively from the bottom walls of the recesses to the inner walls of the carrying member in diametrically opposite relation to each other, whereby one of the openings through the carrying member will be in register with the upper part of said valve casing when the other of said openings in the carrying member is in register with the port in the lower part of the valve casing, and an expandible hollow valve head comprising two cooperative sections in slideable engagement with each other interiorly of the carrying member and extending oppositely through the openings in the latter, said sections having enlarged end portions interfitting the recesses in the peripheral wall of the carrying member, said enlarged end portions having the outer faces thereof curved to conform to the curvature of the inner wall of the valve casing, and expansion springs urging the sections of said expandible valve head apart.

8. In a rotary valve for multi-cylinder internal combustion engines, a tubular valve casing extending across the upper ends of the cylinders and having sets of diametrically opposite openings in the portion thereof overlying each cylinder for establishing communication transversely through the valve casing between a source of supply of combustible fluid and the cylinder and between the cylinder and an exhaust conduit, and means for controlling communication between the respective ports of the two sets for each cylinder, said means including a

rotatable carrying member extending through the valve casing and comprising two axially aligned separable sections coupled together in end to end relation to rotate as a unit and a 5 hollow self-adjusting radially expansible valve head for each cylinder, said radially expansible valve heads being carried by the carrying member to rotate therewith and each being in close contact at its outer ends 10 with the inner wall of the valve casing in position to conduct fluid between the respective ports of each set for one cylinder when the end portions of the valve head are in position to engage with the portions of 15 the valve casing containing said ports.

9. In a rotary valve for multi-cylinder internal combustion engines, a tubular valve casing extending across the upper ends of the cylinders and having sets of diametrically opposite openings in the portion thereof of overlying each cylinder for establishing communication transversely through the valve casing between a source of supply of combustible fluid and the cylinder and between the cylinder and an exhaust conduit, and means for controlling communication between the respective ports of the two sets for each cylinder, said means including a 20 rotatable carrying member extending through the valve casing and comprising two axially aligned separable sections coupled together in end to end relation to rotate as a unit and a hollow self-adjusting radially expansible valve head for each cylinder, said radially expansible valve heads being carried by the carrying member to rotate therewith and being in each being in close contact at its outer ends with the inner wall of the valve casing in position to conduct fluid between 25 the respective ports of each set for one cylinder when the end portions of the valve head are in position to engage with the portions of the valve casing containing said ports, and packing rings disposed between the carrying member and the valve casing in flanking relation to said expansible valve head.

10. In a rotary valve, a tubular valve casing having two diametrically opposite ports 30 opening through the walls thereof, an expansible valve head extending diametrically of the valve casing and having a passage extending therethrough longitudinally thereof, said valve head comprising two cooperative hollow sections, one having the inner end portion thereof slidably interfitting the inner end portion of the latter, said sections being enlarged to provide continuous flanges at the outer ends thereof, said flanges having the outer faces thereof curved to conform to the curvature of the inner wall of the valve casing and said valve head being disposed within the valve casing so that the passage therethrough will be in register at one end 35 with one of said ports of the valve casing

and in register at its other end with the other port of the valve casing when said valve head has been rotated about the axis of the valve casing to a certain position within the latter, spring means urging said sections of the valve head radially outward, and means for rotating the valve head about the axis of the valve casing. 70

11. In a rotary valve, a tubular valve casing having two diametrically opposite ports 75 opening through the walls thereof, an expansible valve head extending diametrically of the valve casing and having a passage extending therethrough longitudinally thereof, said valve head comprising two cooperative hollow sections, one having the inner end portion thereof slidably interfitting the inner end portion of the latter, said sections being enlarged to provide continuous flanges at the outer ends thereof, said flanges having the outer faces thereof curved to conform to the curvature of the inner wall of the valve casing and said valve head being disposed within the valve casing so that the passage therethrough will be in register at 80 one end with one of said ports of the valve casing and in register at its other end with the other port of the valve casing when said valve head has been rotated about the axis of the valve casing to a certain position within the latter, spring means urging said sections of the valve head radially outward, means for rotating the valve head about the axis of the valve casing, and packing means 85 disposed between said valve head rotating means and the valve casing in flanking relation to the flanges at the ends of the sections of said valve head. 90

12. In a rotary valve construction, a tubular valve casing, a hollow tubular member rotating therewith, said tubular casing having an annular groove in the inner wall thereof and said rotatable tubular member having a groove in its outer peripheral wall in concentric relation to the first named groove, a packing ring partially received in the groove in the rotatable tubular member and extending into the groove in the inner wall of the valve casing, said valve casing and said rotatable member each having two diametrically opposite openings located adjacent to the plane of said grooves, and radially expansible valve means abutting said ring for controlling communication between the corresponding openings of the valve casing and the rotatable tubular member. 105 110 115

13. In a rotary valve construction, a tubular valve casing, a tubular member rotating therewith, said tubular casing having an annular groove in the inner wall thereof and said rotatable tubular member having a groove in its outer peripheral wall in concentric relation to the first named groove, a packing ring partially received in the 120 125 130

groove in the rotatable tubular member and extending into the groove in the inner wall of the valve casing, said valve casing and said rotatable member each having two diametrically opposite openings located adjacent to the plane of said grooves, radially expansible valve means abutting said ring for controlling communication between the corresponding openings of the valve casing and the rotatable tubular member, said ring having a lubricant receiving peripheral groove in the outer periphery thereof and having a passage extending radially inward from said groove partway through the ring and then laterally into communication with a groove in the radially expansible means for feeding lubricant from the peripheral groove to said expansible valve means.

14. A rotary valve for internal combustion engines comprising a hollow valve casing extending across the upper end of a cylinder of an engine, said valve casing having two ports through its lower part opening into the upper part of the cylinder and being in alignment longitudinally of the casing, said casing also having two ports through its upper part, the respective second named ports being diametrically opposite the corresponding ports in the lower part of the casing, and valve means comprising a carrying member mounted to rotate in the valve casing about the longitudinal axis of the latter, and a pair of radially expansible hollow valve heads carried by carrying member, each in position to cooperate with the latter to control communication between diametrically opposite ports of the valve casing.

15. A rotary valve for internal combustion engines comprising a hollow valve casing extending across the upper end of a cylinder of an engine, said valve casing having two ports through its lower part opening into the upper part of the cylinder and being in alignment longitudinally of the casing, said casing also having two ports through its upper part, the respective second named ports being diametrically opposite the corresponding ports in the lower part of the casing, valve means comprising a carrying member mounted to rotate in the valve casing about the longitudinal axis of the latter, a pair of radially expansible hollow valve heads carried by carrying member, each in position to cooperate with the

latter to control communication between diametrically opposite ports of the valve casing, said valve heads lying in planes extending diametrically through the casing in angular relation to each other.

60

16. A rotary valve for internal combustion engines comprising a hollow valve casing extending across the upper end of a cylinder of an engine, said valve casing having two ports through its lower part opening into the upper part of the cylinder and being in alignment longitudinally of the casing, said casing also having two ports through its upper part, the respective second named ports being diametrically opposite the corresponding ports in the lower part of the casing, valve means comprising a carrying member mounted to rotate in the valve casing about the longitudinal axis of the latter, a pair of radially expansible hollow valve heads carried by carrying member, each in position to cooperate with the latter to control communication between diametrically opposite ports of the valve casing, said valve heads lying in planes extending diametrically through the casing in angular relation to each other.
